US00D516553S

(12) **United States Design Patent** (10) Patent No.: **US D516,553 S**
Richardson et al. (45) Date of Patent: **** Mar. 7, 2006**

(54) **TABLET COMPUTER ENCLOSURE**

(75) Inventors: **Curtis R. Richardson**, Fort Collins, CO (US); **Douglas A. Kempel**, Fort Collins, CO (US)

(73) Assignee: **Otter Products, LLC**, Fort Collins, CO (US)

(**) Term: **14 Years**

(21) Appl. No.: **29/217,612**

(22) Filed: **Nov. 18, 2004**

(51) LOC (8) Cl. **14-02**

(52) U.S. Cl. **D14/341**

(58) Field of Classification Search ..... D14/341-346, D14/429; D3/218; D18/1, 2, 7, 11; D19/26, D19/59, 60; 178/18.01, 18.03; 345/104, 156, 345/168, 173; 349/12; 434/307 R, 308, 309, 434/317; 361/680-686; 235/462.45

(57) **CLAIM**

The ornamental design for a tablet computer enclosure, as shown and described.

DESCRIPTION

FIG. 1 is an isometric view of a tablet computer enclosure showing my new design.

FIG. 2 is a front view thereof.

FIG. 3 is a top view thereof.

FIG. 4 is a right side view thereof.

FIG. 5 is a left side view thereof.

FIG. 6 is a rear view thereof; and,

FIG. 7 is a bottom view thereof.

The broken lines are shown in the views for illustrative purposes only and form no part of the claimed design.
